UNITED STATES PATENT OFFICE

99,326

DESIGN FOR A COMBINED SUPPORTING TRAY AND BREAD DISPLAY

Philip J. Hauswald, Baltimore, Md., assignor to
The Hauswald Bakery, Baltimore, Md.

Application January 31, 1936, Serial No. 60,933

Term of patent 14 years

To all whom it may concern:

Be it known that I, Philip J. Hauswald, a citizen of the United States of America, residing at Baltimore, and State of Maryland, have invented a new, original, and ornamental Design for a Combined Supporting Tray and Bread Display, of which the following is a specification, reference being had to the accompanying drawing, forming part thereof.

In the drawing,

Figure 1 is a perspective view of a combined supporting tray and bread display, showing my new design; and

I claim:

The ornamental design for a combined supporting tray and bread display, as shown.

PHILIP J. HAUSWALD.
